UNITED STATES PATENT OFFICE.

HUGO HUCKEL, OF NEUTITSCHEIN, AUSTRIA-HUNGARY.

SLIDE-VALVE GEAR FOR FOUR-STROKE CYCLE EXPLOSION-ENGINES.

1,088,580.

Specification of Letters Patent.

Patented Feb. 24, 1914.

Application filed June 29, 1912. Serial No. 706,789.

To all whom it may concern:

Be it known that I, HUGO HÜCKEL, a subject of the Austro-Hungarian Emperor, and resident of Neutitschein, Austria-Hungary, have invented certain new and useful Improvements in Slide-Valve Gears for Four-Stroke Cycle Explosion-Engines, of which the following is a specification.

This invention relates to valve gears for engines.

The object of the invention is to provide a slide valve in one end of the cylinder, in such manner that said valve forms a cylinder head, and may be operated to admit a charge, or exhaust the spent gases.

A further object of the invention is to provide mechanism which will vary the area of the cylinder during the charging and exhausting periods, whereby to obtain the most effective results.

The invention also relates to the specific details of construction and arrangement of parts which will be hereinafter described and particularly pointed out in the claims.

25 In the accompanying drawings:—Figure 1 is a vertical section on line 1—1 of Fig. 2. Fig. 2 is a section on the line 2—2 of Fig. 1. Fig. 3 is a section on the line 3—3, of Fig. 1.

A indicates a cylinder housed at its upper 30 end by a casing A', which forms a chamber A². Below the casing A', the cylinder is provided with an annular exhaust chamber K, having an exit K' to the atmosphere. Communicating with the exhaust chamber 35 and the cylinder A, are outlet openings a^x, through which the spent gases are ejected when the engine is operating.

Operating on the upper end of the cylinder A, and forming the head thereof is a 40 cylindrical slide valve d, formed with a horizontal partition r, having therein an inlet port r', and in the side walls, below the plane of the partition are outlet ports O. The outlet ports coöperate with the outlet 45 ports a^x, during the operation of the engine, as will be explained later on.

Mounted in suitable bearings in the casing A', is a horizontal shaft a, to which is secured an eccentric b. The eccentric is hollow, and is open at its ends to provide ports m', and m², which communicate with the chamber A². In the periphery of the eccentric is an inlet port m³, which communicates with the hollow portion, as clearly 55 shown in the drawings. Surrounding the

periphery of the eccentric is a band or casing C, the lower portion or base of which is provided with lateral flanges c^x, said flanges operating on the upper surface of the horizontal partition r. The flanges operate in 60 guides on the partition formed by flanges t' and t². In the bottom of the casing c, is an inlet port S, which registers with the inlet port r', and is adapted to register with the inlet port m³, in the eccentric, when the latter is rotated.

In operation, the parts are so timed that when the working piston W descends to draw in a charge, the eccentric will operate to move the slide valve d, in the opposite 70 direction and close the outlet ports a^x, and at the same time the inlet port m³, will register with the inlet port S, and a charge will be drawn into the cylinder from the chamber A². The next return stroke of the piston 75 will compress the charge, and the latter will be fired, then upon the next up-stroke of the piston, the eccentric will move the slide valve d, so as to bring the outlet ports o and a^x into registry and the spent gases will be 80 forced out into the exhaust chamber K.

By the construction described, the area of the cylinder at the time the gas is fired, is greater than during the exhaust period, which produces a more effective blow on the 85 piston in one instance, and the gases are more effectually exhausted in another instance.

The eccentric is timed so that the valve and the inlet ports will coöperate with the 90 piston to produce the desired result.

What I claim is:—

1. In a valve gear for four stroke cycle explosion engines, the combination of a cylinder provided with an exhaust port in its 95 side walls, a slide valve operating in the cylinder and forming the head of the latter and controlling the exhaust port, the slide valve having an inlet port, guides on the outside of the slide valve, a casing having 100 a base formed with a passage and operating in the guides, the passage registering with the inlet port in the slide valve, an eccentric mounted to rotate in the casing and formed with an inlet port which, in the 105 rotation of the eccentric, registers with the inlet ports in the casing and the slide valve, means for introducing fuel to the port in the eccentric, and means for operating the eccentric to cause the inlet ports to register 110

for the admission of a charge to the cylinder and to operate the slide valve to close or open the exhaust ports.

2. In a valve gear for explosive engines, the combination of a cylinder formed with exhaust ports, a slide valve having exhaust ports adapted to register with the exhaust ports in the cylinder and forming the head of the latter, said slide valve having an inlet port, an eccentrically mounted rotary valve having an inlet port and mounted on the slide valve to operate the latter to close the exhaust ports in the cylinder and simultaneously open the inlet port in the slide valve to admit a charge to the cylinder, said eccentrically mounted rotary valve also acting to close the inlet port and reverse the movement of the slide valve to open the exhaust ports in the cylinder.
3. In a valve gear for explosion engines, the combination of a cylinder formed with an exhaust port, a sliding valve operating

in the cylinder and forming the head of the latter, said slide valve having an inlet port, a sliding casing mounted on the outside of the slide valve and formed with an inlet port which registers with the inlet port in the slide valve, a rotating element mounted in the casing and formed with an inlet passage adapted to register with the inlet ports in the rotation of said element, means for simultaneously rotating the element and operating the valve to close the exhaust port and admit a charge to the cylinder, said means also acting to open the exhaust port and close the inlet port, and means for admitting a charge to the rotating element.

In testimony whereof I have hereunto set my hand in presence of two witnesses.

HUGO HÜCKEL.
